UNITED STATES PATENT OFFICE

172,226

COMBINATION SOCKET WRENCH AND SCREW DRIVER

Richard C. Evenson, Santa Monica, Calif.

Application March 23, 1953, Serial No. 24,160

Term of patent 3½ years

(Cl. D54—13)

To all whom it may concern:

Be it known that I, Richard C. Evenson, a citizen of the United States and a resident of Santa Monica, California, have invented a new, original, and ornamental Design for a Combination Socket Wrench and Screw Driver, of which the following is a specification, reference being had to the accompanying drawing, forming a part hereof.

Fig. 1 is an enlarged perspective view of a combination wrench and screw driver showing my new design;

Fig. 2 is a side elevational view thereof;

Fig. 3 is an elevational view looking at the left end of Fig. 2; and

Fig. 4 is an elevational view looking at the right end of Fig. 2.

I claim:

The ornamental design for a combination socket wrench and screw driver, as shown.
